The ornamental design for an ice cube tray with lid, as shown and described.

DESCRIPTION

FIG. 1 is a top perspective view showing the front and top sides of the ice cube tray with lids in an open position;
 FIG. 2 is a front elevational view thereof with the lids in the closed position;
 FIG. 3 is a rear elevational view thereof with the lids in the closed position;
 FIG. 4 is a left side elevational view thereof with the lids in an open position;
 FIG. 5 is a right side elevational view thereof with the lids in an open position;
 FIG. 6 is a top plan view thereof with the lids in an open position;
 FIG. 7 is a bottom plan view thereof with the lids in an open position;
 FIG. 8 is a perspective view of the invention with the left lid closed and the right lid in an open position; and,
 FIG. 9 is a top plan view thereof with the lids in the closed position.
